UNITED STATES PATENT OFFICE.

DUANE A. TINKLEPAUGH, OF KANSAS CITY, MISSOURI.

CABLE-GRIP.

SPECIFICATION forming part of Letters Patent No. 394,796, dated December 18, 1888.

Application filed February 6, 1888. Serial No. 263,089. (No model.)

To all whom it may concern:

Be it known that I, DUANE A. TINKLEPAUGH, of Kansas City, in the county of Jackson and State of Missouri, have invented a certain new and useful Improvement in Cable-Grips, of which the following is a full, clear, and exact description, reference being had to the accompanying drawings, forming part of this specification, and in which—

10 Figure I is a perspective view illustrating my invention. Fig. II is a top view of a cast-iron die, showing the groove into which the copper facing is cast. Fig. III is a section taken on line III III, Fig. II, showing the facing in place.

15 My invention relates to an improvement in dies for cable-grips; and my invention consists in features of novelty, hereinafter fully described, and pointed out in the claims.

20 Referring to the drawings, 1 represents a metal die, made of cast-iron or other suitable material, one of which is designed to be set in the inner face of each of the grip-jaws (not shown) by any suitable and well-known means.

25 On the top of the die is formed a groove, 2, preferably semicircular in shape. In the bottom of the groove 2 are a series of holes, 3.

30 4 represents a copper facing or bushing, which is cast into the groove 2, a portion of it entering the holes 3, which forms studs 5, the object of the studs being to prevent the facing from moving endwise and to hold it in a rigid position.

The body of the die, preferably, has side

walls, 6, outside of the groove to form a firm 35 backing to the copper lining, (which is of course a soft metal,) thus keeping it from being spread by the cable end walls, 7, which prevent its longitudinal movement.

The use of the copper lining for cable-grip 40 dies will add very materially to the life of a cable, as it presents a soft-metal bearing or surface to the hard metal of the cable.

I am of course aware that grip-dies have heretofore been lined with Babbitt and other 45 kinds of hard metal, and make no claim as inventor to such.

I claim as my invention—

1. In a cable-grip, the combination of a removable grooved iron die and a copper facing 50 cast in the groove, substantially as described, and for the purpose set forth.

2. In a cable-grip, the combination of the die 1, provided with a groove, 2, and holes 3, and a copper facing, 4, cast in said groove 55 and holes, substantially as and for the purpose set forth.

3. In a cable-grip, in combination with the iron die having a groove, 2, and side walls, 6, a copper facing or bushing fitting in said 60 groove and kept from expansion by said side walls, substantially as and for the purpose set forth.

DUANE A. TINKLEPAUGH.
